UNITED STATES PATENT OFFICE.

DUDLEY RANDOLPH RYALS, OF RICHMOND, VIRGINIA.

TELEGRAPH-POLE.

1,373,979.

Specification of Letters Patent.

Patented Apr. 5, 1921.

Application filed August 16, 1920. Serial No. 403,797.

To all whom it may concern:

Be it known that I, DUDLEY RANDOLPH RYALS, a citizen of the United States, residing at Richmond, in the county of Henrico 5 and State of Virginia, have invented certain new and useful Improvements in Telegraph-Poles, of which the following is a specification.

This invention relates to devices for supporting wires and the like, the device being of the type commonly known as a telegraph-pole.

More particularly the invention relates to a composite pole or support having a concrete or other like base and a structural upper part or body, the latter being preferably formed of structural steel.

One important object of the invention is to improve the general construction of articles 20 of this description.

A second important object of the invention is to provide a base and body so connected that one may be revolved with respect to the other on their mutual axis and when 25 in desired position secured against rotation whereby any error in the directional alignment of the base may be compensated by properly adjusting the body about its vertical axis.

With the above and other objects in view, as will be hereinafter apparent, the invention consists in general of certain novel arrangements of details and combinations of parts hereinafter fully described, illustrated 35 in the accompanying drawings, and specifically claimed.

In the accompanying drawings, like characters of reference indicate like parts in the several views, and:

Figure 1 is a vertical median section through a portion of a telegraph pole embodying the invention.

Fig. 2 is a detail showing a portion of the bottom plan of the connection between the base and body of the invention being a section on the line 2-2 of Fig. 1.

Fig. 3 is a section on the line 3-3 of Fig. 1.

In the embodiment of the invention herein illustrated there is provided a concrete base 50 having opposed channel irons 11 secured to its upper part by means of suitable bolts 12. The upper ends of these channels are flanged outward as at 13 at a distance above the top of the base 10 and securely riveted to these flanged ends is a circular plate 14 forming the base top. Similarly the body of the

pole is provided with a bottom formed by a circular plate 15 to which is securely riveted the structural members 16 of the pole, the latter being connected in any preferred manner as by the lattice members 17.

Passing through the two plates 14 and 15 is a large bolt 18 axially coincident with the common axis of the base and body of the pole. On this bolt are washers 19 and a nut 20, the latter being secured against accidental loosening as by the cotter 21. Thus this bolt swivelly connects the base and body of the pole.

Adjacent the periphery of each of the plates 14 and 15 is a series of closely spaced holes 22 any one of which in one plate may be caused to register with each of the holes in the other plate so that bolts 23 may be passed through registering holes and there held by nuts 24 so as to prevent accidental swiveling of the body on the base.

Now it is well known that most poles of this description are provided with cross arms and that, in setting concrete bases for 80 metallic poles, it frequently happens that the cross arms are found to be out of proper position and set at other than a right angle to the direction of the supported wires. This produces not only an unsightly appearance but in some cases brings the wires too close together or too close to the body of the pole. With the present device the base is set without any particular regard to its position and the body of the pole connected thereto by the large swivel bolt 18. Then the body may be rotated on its axis until the cross arms are in proper position whereupon the bolts 23 may be applied and the body locked immovably to the base.

There has thus been provided a simple and efficient device of the kind described and for the purpose specified.

It is obvious that many minor changes may be made in the form and construction 100 of this invention without departing from the material principles thereof. It is not, therefore, desired to confine the invention to the exact form herein shown and described but it is desired to include all such 105 as properly come within the scope claimed.

Having thus described the invention, what is claimed as new, is:

1. In a pole for supporting wires or the like, a base, a top plate fixed to the base, a body having a bottom plate resting on the top plate of the base, a bolt passing cen-

trally through the plates and constituting a swivel connection for the base and body, and means to lock the plates immovably with relation to each other.

- 5 2. In a pole for supporting wires or the like, a base, a top plate fixed to the base, a body having a bottom plate resting on the top plate of the base, a bolt passing centrally through the plates and constituting a swivel connection for the base and body, said plates each having a series of holes arranged concentrically about said bolt and registerable with each other and other bolts passing through and secured in certain of said registering holes.
- 10 3. In a device of the kind described, a cementitious base, a pair of confronting
- 15

channels secured to said base and projecting thereabove, a circular top plate fixed to said channels and having a centrally disposed opening and a series of openings concentric therewith and adjacent the periphery, a pole body having a circular bottom plate similarly provided with openings similarly arranged and registerable with the openings in the top plate, a bolt constituting a swivel extending through the central openings of said plates and secured therein, and other bolts extending through registering openings of the peripheral series and secured therein.

In testimony whereof I affix my signature.

DUDLEY RANDOLPH RYALS.
